UNITED STATES PATENT OFFICE.

WILLIAM D. HOOVER, OF BEAVER FALLS, PENNSYLVANIA, ASSIGNOR OF ONE-HALF TO JOSEPH T. PARKS, OF MCKEES ROCKS, PENNSYLVANIA.

DESIGN FOR A COMBINED TICKET OR LABEL HOLDER AND MATCH-STRIKER.

44,958.

Specification for Design.

Patented Dec. 2, 1913.

Application filed September 8, 1913. Serial No. 788,751. Term of patent 14 years.

To all whom it may concern:

Be it known that I, WILLIAM D. HOOVER, a citizen of the United States, residing at Beaver Falls, in the county of Beaver and State of Pennsylvania, have invented a new, original, and ornamental Design for a Combined Ticket or Label Holder and Match-Striker, of which the following is a specification, reference being had to the accompanying drawing, forming a part thereof.

The figure is a perspective view of a combined ticket or label holder and match striker, showing my new design.

I claim:—

The ornamental design for a combined ticket or label holder and match striker, as shown.

WILLIAM D. HOOVER.
